UNITED STATES PATENT OFFICE.

WILLIAM S. MINERS, OF FORT WILLIAM, ONTARIO, CANADA.

DESIGN FOR A TOY.

No. 40,170.

Specification for Design.

Patented July 20, 1909.

Application filed April 11, 1908. Serial No. 426,630. Term of patent 7 years.

To all whom it may concern:

Be it known that I, WILLIAM S. MINERS, a subject of the King of Great Britain, residing at Fort William, in the District of Algoma, Ontario, Dominion of Canada, have invented a new, original, and ornamental Design for Toys, of which the following is a specification, reference being had to the accompanying drawing, forming part thereof.

Figure 1 is a side elevation, showing my new design, and Fig. 2 is a top plan view of same.

I claim:

The ornamental design for a toy as shown.
WILLIAM S. MINERS.
